UNITED STATES PATENT OFFICE.

WILLIAM R. KINNEAR, OF NEW CASTLE, PENNSYLVANIA.

SHEET-SEPARATING MACHINE.

1,079,861.

Specification of Letters Patent. Patented Nov. 25, 1913.

Application filed May 24, 1910. Serial No. 563,209.

To all whom it may concern:

Be it known that I, WILLIAM R. KINNEAR, a citizen of the United States, and resident of New Castle, in the county of Lawrence and State of Pennsylvania, have invented certain new and useful Improvements in Sheet-Separating Machines, of which the following is a specification.

The present invention pertains to machines for stripping apart a pile of metallic sheets while the same are in their annealed or "frozen" state, and has for its purpose to provide a machine of that character embodying further improvements over a machine designed for a like purpose and for which I have pending an application for U. S. patent, bearing the Serial No. 518,196 and dated September 17, 1909.

The characteristic of the machine aforementioned lies in that separate and independent means are provided for lifting a part of the sheet and then separating or stripping the sheet thus lifted from the pile, and a further characteristic thereof is that presser feet are employed for holding down the adjacent sheets during the stripping action. As distinct therefrom, the present machine contemplates the use of a single means for first lifting a part of the sheet and then stripping the same from the pile, and for preventing the adherence of other sheets to the sheet being stripped a reciprocating blade is employed which serves the further purpose of assisting in the stripping operation.

Summarily stated, the machine herein disclosed and described embodies an oscillating carrier provided with suction means for slightly lifting a part of the topmost sheets of the pile progressively as the sheets are separated; a means co-operating with the suction means for positively holding to the carrier the edge of the sheet thus raised; mechanism for oscillating the carrier to strip off the sheets; a follower or auxiliary means for assisting in the stripping operation and preventing the adherence of other sheets to the sheet being stripped; and a means for removing the stripped sheets clear of the pile. In this order of reference, the details of construction of these parts and their manner of operation will be explained in the specification following.

In the accompanying drawings, which illustrate the machine by way of example, Figure 1 is a side elevation of a complete

machine; Fig. 2 is a longitudinal sectional view of the machine; Fig. 3 is a top plan view thereof; Fig. 4 is a front elevation of the suction or sheet lifting carrier; Fig. 5 is a transverse sectional view through the carrier, showing one of the suction devices, and; Fig. 6 is a similar view showing one of the sheet gripping devices. Fig. 7 is a similar view to Fig. 2, with some of the parts moved into different positions.

Referring to the several figures more in detail and with like characters of reference indicating corresponding parts in the several views shown, 1 designates the machine supporting frame which is mounted to have vertical movement on the four screw-threaded adjusting bars 2 whereby it may be lowered progressively as the sheets are separated, the means for effecting which adjustment is fully illustrated and described in my co-pending application above referred to, Serial No. 518,196, dated September 17, 1909; and supported by said frame 1 is a frame superstructure 3 which provides the mounting for the operating motor 4, and which with the frame 1 forms the guideways 5 for the sheet stripper or carrier 6.

The carrier 6 is adapted to have oscillating movement within the frame 1 and its structure comprises a pair of quadrant side plates 7 united by an integral and arcuate section 8 which latter, for a part of its movements, rocks upon the pile of sheets to be separated, as will be hereinafter explained. The side plates 7 are supported within the frame through the medium of the shaft 9, which shaft at its opposite ends is journaled within the sliding blocks 10 that reciprocate within the guideways 5; and adjacent their lower ends said side sections 7 carry stub shafts 11 adapted to travel within the arcuate guideways of the depending arms 12 that form an integral part of the frame 13, which in turn is adapted to have slight vertical reciprocating movement within the frame 1 through the medium of the guides 14. Within the carrier 6 is a plurality of suction devices comprising cylinders 15 rigidly secured to a cross head 16 that forms an integral part of the frame 6, and connected with each of the cylinders 15 is a nozzle 17, all of which nozzles are exposed, as at 18, crosswise of and near one end of the arcuate plate 8. Within each of the cylinders 15 is a piston 19 carried by the piston rod 20 and the sev-

eral rods 20 are mounted upon a common cross head 21, which cross head is, through the medium of suitable hangers 22 that straddle the shaft 9, adapted to be reciprocated on the guides 23. For effecting this reciprocation of the cross head 21 and creating suction in the cylinders, each of the hangers 22 has mounted thereon a pair of oppositely disposed rollers 24 that ride upon the cams 25 fixed upon the shaft 9.

Through the mechanism thus far described, the suction devices are adapted to engage with the topmost sheet of the pile A and slightly lift one edge thereof. The suction being applied near the edge of the sheet only one sheet at a time will adhere to the carrier 6. For positively holding this lifted portion the same is gripped by a pair of dogs 26 that are journaled on the shaft 27 carried by the suction carrier 6. Said dogs 26 are thrown inwardly under a lifted edge of the sheet. For imparting action to the dogs 26, the shaft 27 is fitted with a lever 28 whose outer end is connected with the rod 29 and said rod 29 carries opposed rollers 30 coöperating with cams 31 likewise mounted on the shaft 9. The relative position of the cams 25 and 31 is so selected that when the edge of the sheet is lifted, the gripping dogs 26 are given their inward movement, permitting the jaws of the dogs to enter beneath the sheet. During the oscillating movement of the carrier 6, the dogs in that manner hold on to the sheet, thereby stripping it off the pile.

For actuating the suction devices, the shaft 9 has a pinion 32 which, through a train of gears 33, is connected with a pinion 34 that is fixed on shaft 33' of the arm 35 of the frame 1. The pinion 34 derives its movement through the chain 36 which in turn engages with the sprocket 37 that is carried by the shaft 38, said shaft 38 being rotated in turn through the chain and sprocket gearing 39, 40 and 41 from the motor 4 (see Fig. 1). And in order that the train of gearing 32 and 33 may accommodate itself to the oscillating movement of the carrier 6, the several sprockets composing said train of gearing are journaled within a flexible frame consisting of a pair of pivotally mounted arms 42.

Coöperating with the sheet stripper 6 is an auxiliary stripper or follower, which consists of a horizontally disposed blade 43 that is mounted on a carriage 43' that reciprocates in the guideways 44 of the frame 1, the operation of which blade is so timed that immediately the edge of the sheet is lifted, said blade enters thereunder and as the carrier 6 performs its stripping movement the blade 43 follows such movement, and in addition to assisting in the stripping of the sheet, said blade 43 is further service-

able in that it prevents the adherence of any other sheets to the sheet being stripped. The means for imparting movement to the blade 43 consists of the pitman 45 which is connected at one end 46 to the carriage 43' and at its opposite end 47 to a crank arm 48 that is mounted on the shaft 38. For effecting the simultaneous movement of the carrier 6 with the suction device and the dogs 26, and of the blade 43 as above explained and for the correct positioning of these parts at the beginning of each stroke, the blade carrier 43' supports a pair of uprights 50, which through the medium of the rods 51 connect with the journal blocks 10 of the shaft 9. Thus when the carrier 43' advances with the blade, the slides 10, carrying shaft 9, from which carrier 6 is suspended, are pushed forward by the rods 51. As the stub shafts 11 at the beginning 85 of the movement are held approximately stationary by the guide ways in the arms 12, the carrier 6 will, to begin with, rock around the stub shafts. During the continued forward movement of the shaft 9, the stub 90 shafts will be compelled to follow the arcuate path upward of the guide ways, until the carrier 6 ultimately takes the position shown in Fig. 7. It is arranged so that the carrier 6 may rock upon the pile of sheets while 95 performing the greater part of its stripping operation and that it be lifted from the pile at a certain portion thereof, or when it has about completed its stripping movement. To effect this lifting is the function 100 of the vertically moving frame 13. For giving said frame 13 this necessary lifting movement, said frame is connected to the machine frame 1 by the toggles 52, to which are connected the rods 53 and said rods are 105 pivotally secured to arms 54 on the shaft 55. At one end, the shaft 55 carries an arm 56 that connects with a pitman 57 which derives a shifting movement through the medium of the cam 58 that is keyed to the shaft 33'. This arrangement will cause the frame 13 to be raised and the carrier 6 to be swung around its shaft 9, through the engagement of the stub shafts 11 with the guideways of the arms 12. The shaft 9 being at the time situated to the left (see Fig. 7) of shafts 11, the inner arc of the guideway, at its upper end will press against the shafts 11, thus raising them, and with them the plate held to the carrier 6.

As the carrier 6 is lifted, the weight of the machine is partially sustained through the medium of clamps 52' that are disposed to either side of the pile within the guideways 53' and 53'' and one of said clamps 125 has a link connection 54' to a fixed stud 55' on the frame 1, and through a friction roller 56' that rides within a slot 57' of the carriage 43', said links 54' act to bring their respective clamp 52' into clamping engage- 130

ment with one side of the pile of sheets A, and by reason of a lever connection 59' and 60', the other clamp 52' is brought into like engagement with the opposite side of the stack of sheets.

5. It is further arranged that the sheets be removed clear of the pile as they are stripped therefrom, and to accomplish this the machine is provided with a reciprocating carrier 59 that moves within guideways 60 of the frame 1. Said carrier 59 is fitted with gripping devices, comprising each a lower fixed finger 60' and a movable upper finger 61. Said movable finger 61 has a fixed arm 61' which is connected through a link 62 to a two armed lever 63, 63'. In the forward movement of the carrier 59, *i. e.* in the direction for engaging the stripped sheet, the arms 63 are engaged by cam projections 64, on the cross bar 64' thus causing said fingers to close and engage the sheet. The joint between parts 62 and 63 is then thrown slightly beyond the dead center so as to keep the fingers firmly locked over the plate. And 25 on the completion of the rearward movement of the carrier, the arms 63 engage with similar projections 65 and operate to release the gripping devices from the sheet, whereupon the sheets are permitted to fall to the floor or upon a suitable conveyer, whence they are transferred. The carrier 59 derives its movement through the mechanism for actuating the carrier 6 and the stripping blade 43, the means whereof consists of a 35 rack bar 66 secured to the carrier 59, and which engages with a loosely mounted pinion 67, which pinion has in turn a like engagement with the rack bar 68, and the rack bar 68 is secured to the carriage 43'. The 40 two racks 66 and 68 are held in position with respect to the common pinion 67 by means of retaining or guide rollers 69.

Having thus described my invention, what I claim as new therein and desire to secure 45 by Letters Patent is:—

1. In a sheet separating machine, means for engaging the edge of and then stripping the sheets one by one from a pile, and means for removing the stripped sheets.
50. 2. In a sheet separating machine, means for engaging the edge portion of and then stripping the sheets one by one from a pile, means for removing the stripped sheets, and means for positioning said engaging and stripping means for action as the sheets are separated.
55. 3. In a sheet separating machine, suction means for engaging and lifting one portion of a sheet, a carrier for said suction means having gripping members coöperating with said carrier to strip the sheet from the next adjacent sheet, means for preventing the adherence of another sheet to the sheet being stripped, and means for removing the stripped sheet.

4. In a sheet separating machine, means adapted to rest upon the sheets and through suction engage and lift one portion of the topmost sheet and having gripping members adapted to be actuated to effect the stripping of the sheet, and means coöperating therewith for removing the stripped sheet.

5. A machine for separating a pile of sheets comprising a frame adapted to be supported over and lowered progressively with a pile of sheets as the sheets are separated, a carrier mounted in said frame and provided with suction and gripping means for successively engaging and stripping the topmost sheet of the pile, and means coöperating therewith for removing the sheet as stripped.

6. A machine for separating a pile of sheets comprising a frame, a carrier provided with a suction device and with gripping members mounted to oscillate therein and adapted to successively engage with and strip the topmost sheet of the pile, and means coöperating therewith for removing the sheet as stripped.

7. A machine for separating a pile of sheets comprising a frame, a carrier mounted to oscillate therein and having a plurality of suction devices and gripping members adapted to engage with and lift one portion of the topmost sheet of the pile, said oscillating device adapted during its movements to strip off the sheet thus engaged, and means coöperating therewith for removing the sheet as stripped.

8. A machine for separating a pile of sheets comprising a frame, a carrier provided with a suction device and with gripping members mounted to oscillate within the frame and adapted to successively engage with and strip the top sheet from the pile, a follower for said stripping means adapted to prevent the adherence of the sheet adjacent the stripped sheet, and means for actuating said follower and said oscillating carrier.

9. A machine for separating a pile of sheets comprising a frame, a carrier mounted to oscillate therein and having a suction device adapted to engage with and lift one portion of the topmost sheet of the pile progressively as the sheets are separated, said carrier adapted to roll upon the pile of sheets and strip off the sheet so engaged, means for elevating the carrier during a portion of its stripping operation, and means for actuating the carrier and said elevating means.

10. A machine for separating a pile of sheets comprising a frame, a carrier mounted to oscillate therein and having a suction device adapted to engage with and lift a portion of the topmost sheet of the pile, a means associated therewith for positively holding the raised portion of the sheet,

- means for actuating the carrier whereby to strip off the sheet so engaged, and means for removing the stripped sheet.
11. A machine for separating a pile of 3 sheets comprising a frame, a carrier adapted to oscillate therein and having a suction device adapted to raise a portion of the topmost sheet of the pile, a means carried by said carrier and cooperating with the suction device to positively hold the raised portion of the sheet, means for actuating said carrier whereby to strip the sheet from the pile, and means for removing the stripped sheet.
15. 12. A machine for separating a pile of sheets comprising a frame, a carrier adapted to oscillate therein and having a plurality of suction devices adapted to raise a portion of the topmost sheet of the pile, gripping dogs mounted on the oscillating carrier adjacent the suction devices and adapted to positively hold the raised portion of the sheet, means for actuating said carrier whereby to strip the sheet from the pile, and means for removing the stripped sheet.
18. 13. A machine for separating a pile of sheets comprising a frame, a carrier mounted to oscillate within said frame, and provided with a plurality of suction devices arranged adjacent one edge thereof, said suction devices adapted to raise a portion of the topmost sheet of the pile, gripping dogs journaled on said frame adjacent the suction devices and adapted to positively hold the raised portion of the sheet, means for actuating the carrier whereby to strip the sheet from the pile, and a reciprocating gripping means adapted to engage with and remove the stripped sheet.
22. 14. A machine for separating a pile of sheets comprising a frame, a carrier mounted to oscillate within said frame and having gripping members and a plurality of suction devices arranged adjacent one edge thereof, said gripping members and suction devices adapted to grip and raise a portion of the topmost sheet of the pile, means for actuating the carrier whereby to strip the sheet from the pile, said actuating means having a part adapted to follow the oscillating carrier and prevent the adherence of other sheets to the sheet being stripped, and a reciprocating means adapted to engage with and remove the stripped sheet.
26. 15. A machine for separating a pile of sheets comprising a frame, a carrier mounted to oscillate within said frame and adapted to be supported upon the pile of sheets, said carrier frame provided with a plurality of suction devices arranged adjacent one edge thereof, said suction devices adapted to engage with and lift a part of the top sheet of the pile, gripping dogs journaled on said carrier and adapted to positively hold thereto the raised portion of the sheet, a follower adapted to prevent the adherence of sheets to the sheet being separated, a means for simultaneously actuating said carrier and follower for stripping off the sheet from the pile, a means for lifting said carrier clear of the pile during a portion of its stripping movement, and a reciprocating means adapted to engage with and remove the stripped sheet.
30. 16. A machine for separating a pile of sheets comprising a suitably mounted frame, a carrier mounted within said frame and provided with suction means adapted to engage with and lift a portion of the top sheet of the pile, gripping dogs mounted on the carrier adapted to positively hold thereto the raised portion of the sheet, said carrier adapted to be supported by the pile of sheets during said lifting action, means for oscillating the carrier whereby to strip off the sheet, means for lifting the carrier from the pile of sheets during a portion of the stripping operation, a follower adapted to assist in the stripping of the sheet and prevent the adherence thereto of other sheets, means for simultaneously actuating said oscillating carrier and the follower, and a reciprocating gripping device adapted to engage with and remove the stripped sheet.
34. 17. A machine for separating a pile of sheets comprising a suitably mounted frame, a carrier mounted to oscillate therein and provided with gripping members and a plurality of suction cylinders having means for creating suction therein, said suction cylinders and gripping members adapted to lift a portion of the top sheet of the pile progressively as the sheets are separated, a means for actuating the oscillating carrier whereby to strip off the sheet, a flexible gearing connection between said actuating means and the suction creating means whereby to operate the latter, a follower adapted to assist in the stripping of the sheet and prevent the adherence thereto of other sheets, and a reciprocating gripping device adapted to engage with and move the stripped sheet.
38. 18. A machine for separating a pile of sheets comprising a suitably mounted frame, an oscillating carrier mounted therein and adapted to rock upon the pile of sheets, a plurality of cylinders mounted on said oscillating carrier, pistons within said cylinders adapted to create suction therein whereby the cylinders may lift a part of the top sheet of the pile, gripping dogs mounted on the oscillating carrier and adapted to engage with and positively hold the raised portion of the sheet, means for imparting oscillatory movement to said carrier whereby to strip off the sheet, means for lifting the oscillating carrier from the pile during a portion of its stripping operation, a flexible train of gearing connecting the suction creating

means with the actuating means of the oscillating carrier, and a reciprocating gripping device adapted to engage with and remove the stripped sheet.

5 19. A stripping device for a sheet separating machine comprising a frame mounted to oscillate therein and adapted to be rocked upon the pile of sheets to be separated, and a suction means carried by said frame 10 adapted to engage with a portion of a sheet and hold the same during the rocking movement whereby to strip off the sheet.

15 20. A stripping device for a sheet separating machine comprising a frame mounted to oscillate therein and provided with a suction means adapted to engage with and lift a portion of a sheet, and a means mounted on the frame adjacent the suction means adapted to positively hold the raised portion 20 of the sheet during the oscillation of the frame whereby to strip off the sheet.

25 21. A stripping device for a sheet separating machine comprising a frame having an arcuate surface and adapted to be oscillated, a plurality of suction devices exposed in the arcuate surface and adapted to engage with and lift a portion of a sheet, means adjacent the suction devices for positively holding the portion thus raised during the oscillation of the frame whereby to 30 strip off the sheet.

35 22. A stripping device for a sheet separating machine comprising a frame having an arcuate surface and adapted to be oscillated, a plurality of cylinders having noz-

zles exposed in said arcuate surface, means for creating suction within said cylinders whereby to engage and lift a portion of a sheet, gripping dogs mounted adjacent said nozzles for positively holding the portion 40 thus raised during the oscillation of the frame whereby to strip off the sheet, and a flexible gearing connected to said suction creating means whereby to actuate the latter.

45 23. A stripping device for a sheet separating machine comprising a frame having an arcuate surface and adapted to be oscillated, a plurality of cylinders mounted within the frame and having each a suction nozzle exposed in said arcuate surface, pistons 50 within the cylinders adapted to create suction therein, said pistons having rods mounted on a common cross-head, means for reciprocating the cross-head whereby to create suction in the several cylinders simultaneously and cause to be lifted a portion of a sheet, gripping dogs mounted adjacent said nozzles adapted to positively hold the portion thus raised during the oscillation of the frame whereby to strip the sheet, and a flexible train of gearing connected to said suction creating means whereby to actuate the latter.

55 The foregoing specification signed at New York, N. Y., this 17th day of May, 1910.

WILLIAM R. KINNEAR.

In the presence of two witnesses:

M. L. SULLIVAN,

I. M. BLANCHFIELD.
